ABRASIVE WHEEL DRESSING MACHINE

George F. Eglinton, Detroit, Mich., assignor, by
mesne assignments, to Lincoln Park Industries,
Inc., Lincoln Park, Mich., a corporation of
Michigan

Application November 3, 1943, Serial No. 508,784

11 Claims. (Cl. 51—35)

The present invention relates to an abrasive wheel dressing machine for forming, dressing or truing the operative faces of grinding wheels used in form grinding and particularly to such a grinder adapted for the grinding or truing within close precision limits of an abrasive wheel utilized in grinding high precision forms in a work piece.

In the particular embodiment herein disclosed the grinder is employed to dress the grinding edge of an abrasive wheel utilized in the precision grinding of British standard threads on a thread gauge. In such use, it is essential that the shape and dimensions of the grinding wheel be maintained to the desired shape within close precision limits. This is accomplished by first dressing the grinding surface of the grinding wheel to the desired shape and thereafter by truing operations thereon to maintain its desired working form. In the instance just mentioned, a diamond impregnated abrasive wheel is employed as the grinding wheel to grind the desired thread form into the body of the gauge member which is formed of a hard wear resisting material such, for example, as tungsten carbide. The grinding wheel edge is dressed to provide angularly inclined cutting faces thereon which join each other in a small radius to form an arcuate circumferential edge on said wheel. When such a wheel is employed for grinding the body of the gauge, the thread form which results from its use has inclined side portions joined in an arcuate bottom portion corresponding to the shape of the dressed or trued grinding surfaces of the grinding wheel.

It is an object of the present invention to provide an abrasive wheel dressing machine characterized particularly by its accuracy in operation, its relative simplicity of structure and design and its ready adaptability to the grinding or truing of abrasive wheels having different shaped grinding edges, and by means of which the shaped grinding edge is uniformly dressed or trued to a desired form within close precision limits.

Other objects of this invention will appear in the following description and appended claims, reference being had to the accompanying drawings forming a part of this specification wherein like reference characters designate corresponding parts in the several views.

In the drawings:

Fig. 1 is a fragmentary perspective of a machine for dressing the working surfaces of an abrasive grinding wheel, the machine embodying the present invention being shown in its op-

erative position for dressing a diamond impregnated abrasive grinding wheel.

Fig. 2 is a top plan of the dressing machine shown in Fig. 1.

Fig. 3 is a side elevation with parts broken away of the machine shown in Fig. 1.

Fig. 4 is a sectional view taken substantially on the line 4—4 of Fig. 2 looking in the direction of the arrows.

Fig. 5 is an elevation taken substantially along the line 5—5 of Fig. 3 looking in the direction of the arrows.

Fig. 6 is a view similar to Fig. 2 but showing in addition to the dressing of the one inclined face of the grinding wheel the dressing of the opposite inclined edge of the grinding wheel when the parts are moved to the position shown in the dotted line portions of this view.

Fig. 7 is an enlarged simplified view showing the position of the dressing wheel during the dressing of the grinding surface of the grinding wheel.

Fig. 8 is a section taken substantially on the line 8—8 of Fig. 2 looking in the direction of the arrows.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

A machine of the present invention may be constructed, and operated as a single independent unit, or it may be mounted and used as a sub-assembly on a grinding machine. In either instance it is mounted on a fixed base 10 which supports an arcuate fixed base plate 11 having a concentric arcuate guide way 12 extending through the face and a peripheral way 13 formed in the circumferential edge thereof. The peripheral way 13 is adapted to guide a clamp lip 14 and provide an edge for the adjustable clamping of the grinding fixture by the adjustable clamp 15 into a variety of adjusted positions.

The entire wheel dressing unit is mounted on a plate 16 which is pivotally mounted at the pivot point 17 on the base plate 11. The plate 16 carries a guide member 18 mounted for movement in the way 12 and also carries the clamping member 15 at a point adjacent the circumferential portion of the base 11. Thus the plate

16 may be adjustably swung about the pivot 17 relative to the fixed plate 11 when the clamping member 15 is loosened. The plate 16 may be held in any desired adjusted position relative to the plate 11 by the clamping action of the clamp 15 in the peripheral way 13 of the fixed plate 11.

An adjustable slide member 20 is carried in ways 21 and 22 which are mounted on the pivotal plate 16. The adjustable slide member is held in a predetermined position in the ways 21 and 22 by adjustment of the slide adjusting screw member 23.

Mounted on the slide 20 is a fixed plate and guide member 24 on which is mounted the base portions of ball slides 25 and 26. The movable portions 27 and 28 of said ball slides are carried by slide plate members 29 and 30 forming the sides of the movable power head member which is carried on bar slide members 31 and 32 respectively. The movable power head member comprises a base portion 33 having a motor supporting bracket 34 carrying an adjustable motor clamping member 35 to which is secured a high speed electric motor 36 mounted for driving the drive pulley 37. An idler guide pulley 38 is mounted on the base portion 33 and guides the power transmission belt 39 which drives the power pulley 40 of a high speed grinding spindle 41 at the opposite end of which is mounted the dressing wheel 42.

The high speed grinding spindle 41 is mounted on a reciprocating slide bracket 43 which is carried on ball slides 44 and 45 which are mounted on the base 33.

The reciprocating slide bracket 43 is vertically reciprocated in the ball slides 44 and 45 by the electric motor 46 which drives, through a gear reduction 47, an eccentric 48 which is connected with a connecting rod 49 which is pivotally connected with brackets 50 on top of the slide bracket 43.

The motor 46 and the gear reduction 47 is mounted on a motor supporting bracket 51 secured to the base 33.

An index guide plate 52 provided with a plurality of index guide holes 53 is secured to a fixed plate 24 directly beneath the side plate 29. An index pin 54 is carried in a bracket 55 which is secured to the side of the plate 29 and is provided with a locking slot 56 for holding a locking pin 57 attached to the index pin 54.

Thus the base 33 and all the attached parts may be selectively locked against sliding movement by movement of the index pin 54 in the bracket 55 so as to bring the pin into position for locking in any one of the plurality of index guide holes 53. To permit sliding movement of the base 33, the index pin 54 is withdrawn from the index guide holes 53 and is held out of contact therewith by the action of the locking slot 56 on the locking pin 57 carried by said index pin 54.

Sliding movement of the base 33 relative to the fixed plate 24 is effected and controlled by a manually actuated knob 58, which as shown in Fig. 4, is keyed to the end of the rotatable shaft 59 which is journaled in the side plates 28 and 30, and the sleeve bearings 60 and 61 journaled in the bar slide members 31 and 32 carried by the base portion 33.

A pinion gear 62 is keyed on the shaft 59 for rotation therewith and meshes with a stationary rack gear 63 secured to the fixed plate 24.

The knob 58 may be removed from the end of the shaft 59 as here shown, and if desired may

be placed on the opposite end thereof when the pivoted plate is moved to the dotted line position shown in Fig. 6.

The dressing wheel truing fixture is carried on a base portion 70 which is removably supported on the stationary base 11. The fixture, as shown in Figs. 2 and 8, comprises a dressing tool holder 71 carried by the said base portion 70. A diamond pointed dressing tool 72 is secured in the dressing tool holder 71 by a plurality of set screws 73 and 74 and is moved into adjusted wheel dressing position relative to the dressing wheel 42 by movement of the tool adjusting set screw 75. As shown in Fig. 8, the base 70 of the dressing wheel truing fixture is provided with a depending stud 76 which is received in a hollow bushing 77 mounted in the fixed base 11. This construction permits the bodily removal of the wheel truing fixture during the wheel dressing operations as hereinafter more fully described and provides a fixed positive positioning of said fixture when truing the dressing wheel 42.

To assure accurate positioning of the pivotal plate 16 when moved to the position shown in Fig. 1, a stop 78 is provided in the slot 11 in a position to contact the guide 18. When moved to the opposite position the guide 18 contacts the end of the slot 12. Thus the pivotal plate 16 is definitely held in predetermined position at each end of the arc through which it is moved during the grinding wheel dressing or truing operations.

The operation of a machine embodying the present invention is as follows:

The grinding wheel 79 which is to be dressed or trued is here shown as a diamond impregnated abrasive wheel and is mounted on a power driven grinding spindle 80. It is to be understood however that any other desired type of grinding wheel may be used in place thereof. As here shown, particularly in Fig. 7, the wheel 79 has a grinding edge portion formed by flat inclined faces 81 and 82 joined in the arcuate circumferential face 83. Such a grinding wheel is used in grinding tungsten carbide thread gauges and is formed, dressed, or trued by causing the dressing wheel 42 to dress or true the flat inclined faces 81 and 82 and the arcuate face 83. It is to be understood, however, that by suitable adjustments other types or shapes of grinding surfaces may be formed, dressed or trued on any desired type of grinding wheel. The present invention is, therefore, not limited to the forming, dressing, or truing of this particular wheel.

When the machine of the present invention is positioned as shown in Figs. 1 and 2, and in the solid line portion of Fig. 6, the dressing wheel 42 dresses or trues the inclined face 82. When moved to the dotted line position of Fig. 6 it is in position to dress or true the inclined face portion 81. In moving from the solid line position of Fig. 6 to the dotted line position thereof or vice versa, the index pin 54 is locked in a suitable index guide hole 53 so that as the plate 16 is swung about the pivot 17, the pivot 17 will act as the center which is required to generate a true arcuate face 83 on the grinding wheel 79.

With all sliding portions of the machine thus locked, the swinging of the plate 16 carries the dressing wheel over the arcuate face 83 of the grinding wheel in a fixed predetermined arcuate path as may be required to generate the arcuate face 83. It is preferable that the dressing opera-

tions on the inclined faces 81 and 82 be completed prior to formation or truing of the arcuate face 83, although, as above stated, it may be worked upon during the movement of the dressing wheel from one side to the other of the grinding wheel.

In dressing or truing the inclined faces 81 or 82, the plate 16 is swung into the required adjusted position to align the dressing wheel 42 with the face to be dressed or trued and the index pin 54 is retracted from the index hole 53. The manually actuated knob 58 is then rotated manually to move the dressing wheel 42 back and forth across the face of the grinding wheel which is to be dressed or trued. During all the times that the dressing wheel 42 is in dressing or truing position relative to the wheel 79, it is rotated by the power drive to the high speed spindle 41, which in a preferred embodiment, will be in the order of approximately ten thousand revolutions per minute. At the same time the dressing wheel 42 is moved and reciprocated vertically by the motor driven connecting rod 49. Thus the dressing wheel 42 is moved bodily both vertically and horizontally relative to the surface to be dressed or trued at the same time that it is rotated while in contact with the surface which is to be dressed or trued. During the dressing or truing operation, the grinding wheel 79 is rotated at approximately its normal grinding speed. Variations in the generated surfaces due to irregularities in either the grinding wheel surface or in the dressing wheel surface are thus largely eliminated as the movements of the wheels during the dressing or truing operations cause any such irregularities to be effective only over the entire operation.

After performing several dressing or truing operations on the grinding wheel 79, it is advisable to true the dressing wheel 42. In this operation, as shown in Fig. 8, the diamond wheel truing tool fixture is placed on the base 11 and the diamond truing point of the tool 72 is brought into adjusted position on the periphery of the dressing wheel 42. The wheel 42 is rotated and reciprocated horizontally and vertically relative to the tool 72 until the dressing surface thereof is restored or trued as may be desired. Due to the removal of a portion of the wheel 42 on each truing operation, the adjusting member 23 is suitably adjusted to move the slide 20 and thus to compensate for any change in the diameter of the wheel 42. This is accomplished by bodily moving the entire unit closer to the working surfaces of the grinding wheel 79. The adjusting member 23 also is utilized to permit the use of dressing wheels of various sizes, for by its adjustment, the slide 20 is moved as required to compensate for such differently sized dressing wheels, and assures that the dressing wheel surface will be brought into suitable wheel dressing contact with the grinding wheel with which the device is to be used.

It is to be understood that while a machine of the present invention is particularly suited for the uses herein described, it is not expressly limited thereto as it may be readily adapted for numerous uses of a similar or related nature by slight modifications and adjustments which may be readily effected by any mechanic skilled in the art. It will be seen, therefore, that a machine as herein described provides a suitable device for accurately dressing or truing the working surfaces of a grinding wheel within close precision limits.

Having thus described my invention, what I

desire to secure by United States Letters Patent is:

I claim:

1. A machine for dressing or truing the working surface of a grinding wheel and comprising a fixed base, a pivoted plate movable thereon about a fixed center, a power driven rotatable dressing wheel carried on said pivotal plate and mounted for horizontal and vertical reciprocation relative to the said working surface of the said grinding wheel.
2. A machine for dressing or truing the working surface of a grinding wheel and comprising a fixed base, a pivoted plate movable thereon about a fixed center, a power driven rotatable dressing wheel carried on said pivotal plate and mounted for horizontal and vertical reciprocation relative to the said working surface of the said grinding wheel, and adjustable means for moving said dressing wheel bodily toward and away from said working surface of said grinding wheel to permit the use of different sizes of dressing wheels on said machine.
3. A machine for dressing or truing the working surface of a grinding wheel and comprising a fixed base, a pivoted plate movable thereon about a fixed center, a power driven rotatable dressing wheel carried on said pivotal plate, and means including a manually actuated slide member for moving said dressing wheel horizontally and a power actuated reciprocating slide member for moving said dressing wheel vertically relative to the said working surface of the said grinding wheel.
4. A machine for dressing or truing the working surface of a grinding wheel and comprising a fixed base, a pivoted plate movable thereon about a fixed center, a power driven rotatable dressing wheel carried on said pivotal plate and means including a manually actuated slide member for moving said dressing wheel horizontally and a power actuated reciprocating slide member for moving said dressing wheel vertically relative to the said working surface of the said grinding wheel, and adjustable means for moving said dressing wheel bodily toward and away from said working surface of said grinding wheel to permit the use of different sizes of dressing wheels on said machine.
5. In the method of dressing the working surface of a grinding wheel, the novel step of rotating a dressing wheel across the working surface of said grinding wheel while bodily moving said dressing wheel horizontally and vertically relative to said grinding wheel.
6. In the method of dressing the working surface of a grinding wheel, the novel step of rotating a dressing wheel across the working surface of said grinding wheel while moving said dressing wheel horizontally and vertically relative to said grinding wheel, while maintaining an adjusted set position of said dressing wheel relative to the working surface of said grinding wheel thereby to dress a working surface on said grinding wheel to a predetermined contour within close precision limits.
7. In the method of dressing the working surface of a grinding wheel, the novel step of rotating a dressing wheel across the working surface of said grinding wheel while moving said dressing wheel horizontally and vertically relative to said surface, and swinging said dressing wheel into a plurality of adjusted positions for dressing the opposite sides and edge portion of the working

surface of said grinding wheel within close precision limits.

8. In a method of dressing the working surface of an abrasive grinding wheel, the novel step of rotating a dressing wheel across the said working surface while moving said dressing wheel horizontally and vertically relative thereto and maintaining an adjusted set position of said dressing wheel relative to said working surface to dress said working surface to a predetermined contour within close precision limits, and swinging said dressing wheel into a plurality of adjusted positions for dressing the various portions of said working surface.

9. A machine for dressing the working surface of a grinding wheel and comprising a fixed base, a pivoted plate movable thereon about a fixed center, a power driven rotatable dressing wheel carried on said pivotal plate and mounted for horizontal and vertical reciprocation relative to the said working surface of the said grinding wheel, and a manually adjustable clamp for securing said pivoted plate to said fixed plate in a plurality of selected adjusted positions.

10. A machine for dressing the working surface of a grinding wheel and comprising a fixed base, a pivoted plate movable thereon about a fixed

center, a power driven rotatable dressing wheel carried on said pivotal plate and mounted for horizontal and vertical reciprocation relative to the said working surface of the said grinding wheel, adjustable means for moving said dressing wheel bodily toward and away from said working surface of said grinding wheel to permit the use of different sizes of dressing wheels on said machine, and a manually adjustable clamp for securing said pivoted plate to said fixed plate in a plurality of selected adjusted positions.

11. A machine for dressing the working surface of a grinding wheel and comprising a fixed base, a pivoted plate movable thereon about a fixed center, a power driven rotatable dressing wheel carried on said pivotal plate and mounted for horizontal and vertical reciprocation relative to the said working surface of the said grinding wheel, and including a manually actuated slide member for moving said dressing wheel horizontally and a power actuated reciprocating slide member for moving said dressing wheel vertically relative to said working surface, and a manually adjustable clamp for securing said pivoted plate to said fixed plate in a plurality of selected adjusted positions.

GEORGE F. EGLINTON.
